SECTIONAL POST LOCK FOR LOOSE-LEAF BINDERS

Walter Shoda, St. Albans, N. Y.

Application July 20, 1946, Serial No. 685,257

3 Claims. (Cl. 129—12)

1.

This invention relates to loose leaf binder locking means and in particular to one providing a sectional post construction that is locked from the top.

A particular object of the invention is to provide, in a structure of the character referred to, a lock strip which is yieldably held in locked position and which is operated under pressure to afford release of the parts of the device.

Another object of the invention is to provide, in connection with the construction referred to, means for locking the lock strip in operative position so that it cannot be accidentally released.

Other important objects of the invention are the provision of post jamming means of simplified construction that may be operated in unison by depressing a control member to release separable parts of the device so that access to the bound sheets is afforded; and to provide a structure in which a minimum number of parts are employed for carrying out the operation of locking the parts together, releasing said parts and rendering the device foolproof.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a view in side elevation of a loose leaf binder showing the adaptation thereto of the improved locking means.

Fig. 2 is a view in perspective of the tubular clamping members shown in assembled contacting relation.

Fig. 3 is a section on the line 3—3 of Fig. 2, an opened position of one of the clamping members being shown in outline.

Fig. 4 is a view in perspective of the bottom clamp member.

Fig. 5 is a view in cross section, similar to Fig. 4, but showing the guide posts and adjusting screw in full lines.

Fig. 6 is a view in perspective of the lock strip employed in the upper tubular clamping member.

Fig. 7 is an edge view of the locking strip illustrated in Fig. 6 in the position it assumes when the clamps are held together in locked relation.

Fig. 8 is a view similar to Fig. 7 showing the position assumed by the lock strip when the clamps are released.

Fig. 9 is a fragmentary view in section of the

2.

lock strip adjusting screw shown in the position it occupies when in a locked condition.

Fig. 10 is a view similar to Fig. 9 showing the adjusting screw in an unlocked condition.

Fig. 11 is a view similar to Fig. 10 but showing the device prior to the insertion and riveting of the pin.

Fig. 12 is a view in perspective of a modified form of wedging plate that may be used in connection with the locking strip.

Referring to the drawings in detail, 10 indicates a clamping member comprising upper and lower portions 11 and 12 respectively. The upper portion 11, as well as the lower portion, is shaped to provide a flat tubular clamp of hollow rectangular form in the upper surface of which is provided post openings 13 adjacent the opposite ends thereof and intermediate said post openings a hole 14 through which passes freely, the threaded body 15 of an adjusting screw 16. The threaded body 15 of the screw has threaded engagement with a collar 17 welded or otherwise secured to the underside of a lock strip 18 at the center thereof. The lock strip is made from a piece of highly tempered flexible metal positioned within and bearing against the underside of the top of the upper housing or clamp 11 and extending lengthwise thereof between said post holes 13.

The strip, intermediate its opposite ends and the central threaded opening 19 thereof, is laterally ridged as at 20 to provide a fulcrum at opposite sides of the adjusting screw 16, the outer ends of the lock strip having loosely secured thereto, as by rivets 21, the wedge or friction plates 22 each of which is provided with a flanged outer edge 23 having a notch 23a therein and an opening 24 which is arranged to encompass a post 25 when the wedge plate 22 is resting in its inclined position, as illustrated in Fig. 3. The posts 25 which may be made in sections, are fixed in the bottom of the lower clamping member 12 and extend through openings 25a in the upper surface thereof.

The rising of the outer free ends of the lock strip 18 will bring the wedging plates 22 to horizontal position so that the openings 24 therein will move out of contact with the diametrically opposite sides of the posts 25 to permit the clamp 11 to be lifted off said posts. When the locking strip is in the position shown in Fig. 3 the outer ends thereof will be in their locked position. The flange 23 on the outer end of each wedge plate supports the latter in an inclined or oblique position so that the opposite sides of the opening 24 in each plate frictionally engages the opposite

sides of the post 25 passing therethrough and prevents the removal of the clamping member 11 from the posts 25.

As is well understood in these devices, the clamping elements 11 and 12 are usually incorporated in the inner sides of covers 26 which form a binder for loose leaf pages 27 which are passed over the posts 25. These records are usually of a confidential nature and it is desired that they be effectively locked in the book in which they are bound, the locking screw 16 being permanently associated with the book. The locking or adjusting screw 16 is preferably made, as best shown in Fig. 10, of a threaded portion 15, the lower end of which is reduced to provide a pin 31 which is rotatively received in an aperture 32, in the bottom wall of the clamp 11, the end of the pin being peened over to hold the locking screw in place. The upper end of the locking screw has a reduced pin 31' which tightly fits in an aperture provided in a disc 16', the outer peripheral rim of which is knurled to provide a finger grip surface. Body portion 15 of the locking screw is threaded in the locking strip 18 and its collar 17. The locking screw is rotated to raise the locking strip to its upper position, as shown in Fig. 9, for locking the device. By turning the locking screw in the opposite direction, locking strip 18 is flexed downwardly, as shown in Fig. 10, to turn wedge plates 22 to horizontal position to unlock the clamps in the manner described above.

In a modified form of the structure the wedge plates 33 are each formed to provide an opening 34 and a solid lip or flanged portion 35 which permits the wedge plate to assume a horizontal position when the lock strip is operated.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a loose leaf binder, upper and lower clamp members, posts extending from the lower clamp and passing through said upper clamp, a flexible strip in said upper clamp, perforated wedge plates connected to the opposite ends of said strip and through the perforations in which said posts pass, means for positioning said plates obliquely whereby the posts are frictionally engaged by the diametrically opposite edges of the perforations to lock the clamp members together, means for flexing said strip to move the plates from oblique to horizontal positions to free said posts and said locking strip being ridged at opposite sides of said flexing means to provide fulcrums whereby the opposite outer ends of said strip move vertically to move said plates.

2. In a loose leaf binder, upper and lower clamp members, posts extending from the lower clamp and passing through said upper clamp, a flexible strip in said upper clamp, perforated wedge plates connected to the opposite ends of said strip and through the perforations in which said posts pass, means for positioning said plates obliquely whereby the posts are frictionally engaged by the diametrically opposite edges of the perforations to lock the clamp members together, said strip being normally in flexed position to retain the plates in oblique locking position, adjustable means for flexing said strip to move the plates from oblique locking position to free said posts, said strip flexing means comprising a screw and a threaded collar on said strip through which the screw passes and said locking strip being ridged at opposite sides of said flexing means to provide fulcrums whereby the opposite outer ends of said strip move vertically to move said plates.

3. In a loose leaf binder, upper and lower clamps, posts extending from the lower clamp and passing through said upper clamp, a flexible strip in said upper clamp, perforated wedge plates having edges loosely connected to the opposite ends of said flexible strip, said post also passing through the perforations of said wedge plates, means for positioning said plates obliquely whereby the posts are frictionally engaged by the diametrically opposite edges of the perforations to lock the clamps together, said strip being normally in flexed position to retain the plates in oblique locking position, adjustable means for flexing said strip to move the plates from oblique locking position to free said posts, said strip flexing means comprising a screw and a threaded collar on said strip through which the screw passes, said upper clamp having an opening formed in the bottom thereof, said screw having a reduced lower end portion disposed within said opening and freely rotatable therein, means on said screw cooperating with said upper clamp to prevent detachment of said screw from said upper clamp, said wedge plate positioning means comprising a lip on the edge of each of said wedge plates opposite the edges of which are loosely connected to the ends of said flexible strip, said flexible strip being ridged on opposite sides of said flexing means to provide fulcrums whereby the opposite outer ends of said strip will move vertically to move said wedge plates.

WALTER SHODA.
